UNITED STATES PATENT OFFICE.

JOHN C. DE PENNING, OF PORTLAND, OREGON, ASSIGNOR TO CENTRAL DOOR AND LUMBER COMPANY, OF PORTLAND, OREGON, A CORPORATION.

PANEL CLAMP.

Application filed November 4, 1926. Serial No. 146,147.

My invention relates to clamps, vises and the like and the principal object of my invention is to provide a convenient and efficient device in which door panels can be assembled and the strips making up such panels positioned and forced into engagement with each other, in a quick and easy manner.

The door panels for which my invention is particularly adapted are composed of strips of ceiling or similar material having tongue-and-grooved edges. Such strips must be subjected to lateral pressure to force said edges into engagement with the strips at each side and inasmuch as the panels must be a definite overall width the strips must be selected to give the panel such width.

A further object of my invention is to provide a device of this character in which such strips will be correctly positioned relatively to each other and be forced into engagement with the adjacent strips, which device will indicate quickly whether said built-up panel is the correct width, or not, and if not, such clamping device is arranged to be quickly loosened and a proper strip or strips inserted to make such panel the proper width.

Panels of this character are not held together sufficiently by the engagement of the tongue-and-grooved edge portions to be handled, and thus tying and stiffening members must be provided for this purpose.

A further object of my invention therefore, is to provide a device for positioning such latter members on the panel, and permitting them to be fastened thereto when the latter is under pressure and the tongue-and-grooved edges are in firm engagement. Devices must also be provided for preventing such panels from buckling under the lateral pressure, and such devices must be arranged so as not to interfere with the location and fastening of such stiffening members.

I attain these objects in a clamp or press comprising a frame having a top portion constituting a bed upon which such panels can be assembled. Surrounding such bed are pairs of spaced gripping members fastened to the frame and defining a mouth which may be contracted to the exact size of the panel to be built. One of the gripping members at the side of the panel and

on the frame, and the free ends of such members are provided with cooperating pressure applying devices adapted to engage each other and to draw such members together to apply pressure to the edges of the panels. Auxiliary means are provided for moving the pivoted end member, quickly and easily, to aline the strips in such mouth and lugs are arranged on the faces of the gripping members to overlie such strips and prevent them from buckling upwardly from the bed. Pairs of such lugs are arranged at the corners of such mouth and extend into the latter such a distance that they engage and position the stiffening members relatively on the panel strips so that the whole assembly can be fastened by screws or similar fastening means. That is, the corner lugs perform a double duty, namely, to hold the panel against buckling and also to position and hold such stiffening members.

The details of construction and the mode of operation of my improved panel clamp are hereinafter described in greater detail, and with reference to the accompanying drawings, in which:

Fig. 1 is a perspective view of the clamp with the two pivoted clamping members swung open;

Fig. 2 is a similar view with panel strips arranged side by side in the mouth of such clamp; and

Fig. 3 is a perspective view of such clamp with the members engaged and gripping a completed panel.

My improved panel clamp comprises a table-like frame *a* having four legs *a'* at its corners, and a top constituting a bed *b* for the panels to be assembled upon. Such top is made up of four bounding angles *a²* and spaced central transverse members *a³*. A sufficient number of such transverse members *a³* are provided to adequately support a number of panel strips *c* placed thereon. A solid top would suffice but would add to the weight of the clamp to render it less portable. At each end of the top an extra wide transverse member or a number of transverse members are arranged side by side to provide an unbroken surface for holding the ends of the panel strips. The extra width of the members at these points permits a wide range of panels to be accommodated.

A pair of clamping members *d* and *e* are arranged at the ends of the clamp and an

other pair *f* and *g* are arranged at the sides thereof. One of said end clamping members *d* is secured to the bed of the frame by bolts *h* which pass thru holes *i* of substantially larger diameter to permit such clamping member *d* to be adjusted over the bed of the frame and fastened in adjusted position. The side clamping member *f* is similarly fastened by bolts *h'* which pass thru similar holes *i'*.

The remaining clamping members *e* and *g* are pivotally mounted to the bed of the frame, the member *e* being mounted upon a pin *j* and the member *g* upon a pin *j'*, both members being thus free at one end which may be swung outwardly from the mouth *k* to receive the panel strips, the mouth being that portion of the bed bounded by the clamping members *e*, *f*, *g*, and *h*.

A pin 1 extends upwardly from the bed, as is shown in Fig. 1, to limit the movement inwardly of the clamping member *e*, the pivoted member *g* needing no such stop because its forked end *g'* is arranged to abut against the end *e'* of the member *e*. A screw *m* is carried by such latter end *e'* and a hand wheel *n*, threaded thereon, has a shoulder *n'* which engages the outer face of the forked end *g'* and draws such end inwardly to close the mouth *k*, the end *e'* serving to limit the movement inwardly of the end *g'*, as has been noted heretofore.

The free end *e'* of the member *e* is forced inwardly by a bell-crank lever *o* pivotally mounted on a pin *p*, extending laterally from the frame *a*. Such lever is arranged to engage a wedge-shaped bracket *q*, on such member *e*, and as it rides up such bracket it forces the free end *e'* towards the stopping pin 1.

Upon the inner faces of the members *d*, *e*, *f*, and *g*, are a number of lugs *r* which are spaced above the bed of the clamp a distance slightly in excess of the thickness of the panel. Such lugs thus serve to hold the panel to the bed of the clamp and prevent it from buckling. The lugs in the corners of the mouth serve a dual purpose in that they extend inwardly from the clamping members a predetermined distance. Diagonal tying and stiffening members *c'* are fastened to the panel strips and such corner lugs serve to position such stiffening members on the panel and to hold them so that they cannot shift when they are being fastened in place. Such corner lugs are arranged relatively to the faces of the clamping members so that they will engage the stiffening members firmly only after the panel strips have been compressed to the desired degree.

I claim:

1. A device of the character described comprising a frame having a top portion constituting a bed, pairs of spaced gripping

members carried by such frame and mounted at opposite sides of said bed and bounding the latter to define a mouth thereon, one member of each pair of gripping members being pivotally mounted at one end to the frame for relative movement over said bed, and means for drawing such free ends of such gripping members together and gripping an article held in such mouth.

2. A device of the character described comprising a frame having a top portion constituting a bed, pairs of spaced gripping members carried by such frame and mounted at opposite sides of said bed and bounding the latter to define a mouth thereon, one member of each pair of gripping members being pivotally mounted at one end to the frame for relative movement over said bed, and cooperating pressure applying devices carried by the free ends of such pivoted members for drawing such free ends of such gripping members together and gripping an article held in such mouth.

3. A device of the character described comprising a frame having a top portion constituting a bed, pairs of spaced gripping members carried by such frame and mounted at opposite sides of said bed and bounding the latter to define a mouth thereon, one member of each pair of gripping members being pivotally mounted at one end to the frame for relative movement over said bed, the free end of one of said pivoted members being provided with a threaded screw element, the free end of the other being provided with a forked end adapted to engage therewith, thereby to draw such free ends together and to grip an article held in such mouth.

4. A device of the character described comprising a frame having a top portion constituting a bed, pairs of spaced gripping members carried by such frame and mounted at opposite sides of the bed and bounding the latter to define a mouth thereon, one member of each pair of gripping members being pivotally mounted at one end to the frame for relative movement over said bed, the free end of one of said pivoted members and the frame being provided with cooperating pressure applying devices adapted to move such free end over such bed.

5. A device of the character described comprising a frame having a top portion constituting a bed, pairs of spaced gripping members carried by such frame and mounted at opposite sides of said bed and bounding the latter to define a mouth thereon, one member of each pair of gripping members being pivotally mounted at one end to the frame for relative movement over said bed, the free end of one of said pivoted members being provided with a threaded screw element, the free end of the other being provided with a forked end adapted to engage

therewith, thereby to draw such free ends together and to grip an article held in such mouth, and the member carrying such screw element and the frame being provided with auxiliary pressure applying devices adapted to move such free end over such bed.

6. A device of the character described comprising a frame having a top portion constituting a bed, pairs of spaced gripping members carried by such frame and mounted at opposite sides of the bed and bounding the latter to define a mouth thereon, one member of each pair of gripping members being pivotally mounted at one end to the frame for relative movement over said bed, the free end of one of said pivoted members and the frame being provided with co-operating pressure applying devices adapted to move such free end over such bed, such 20 pressure applying devices comprising a

wedge-shaped engaging portion and a pivoted lever, one being carried by the frame and the other by the gripping member.

7. A device of the character described comprising a frame having a top portion 25 constituting a bed, pairs of spaced gripping members carried by such frame and mounted at opposite sides of the bed and bounding the latter to define a mouth thereon, one member of each pair of gripping members being pivotally mounted at one end to the frame for relative movement over said bed, the free end of one of each of said pairs of members being provided with pressure applying means, and the remaining members 30 being provided with means for adjustably securing themselves to the bed of the frame to vary the dimensions of such mouth.

JOHN C. DE PENNING.
